(57) **CLAIM**

The ornamental design for a garden arch trellis as shown and described.

DESCRIPTION

FIG. 1 is a front, right and top perspective view of a garden arch trellis, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the garden arch trellis of FIG. 1 shown in a first configuration.

FIG. 10 is another front, right and top perspective view of the garden arch trellis of FIG. 1 shown in a second configuration.

FIG. 11 is another front, right and top perspective view of the garden arch trellis of FIG. 1 shown in a first environment of use.

FIG. 12 is another front, right and top perspective view of the garden arch trellis of FIG. 1 shown in a second environment of use.

FIG. 13 is another front, right and top perspective view of the garden arch trellis of FIG. 1 shown in a third environment of use.

FIG. 14 is another front, right and top perspective view of the garden arch trellis of FIG. 1 shown in a fourth environment of use.

FIG. 15 is another front, right and top perspective view of the garden arch trellis of FIG. 1 shown in a fifth environment of use.

FIG. 16 is another front, right and top perspective view of the garden arch trellis of FIG. 1 shown in a sixth environment of use.

FIG. 17 is another front, right and top perspective view of the garden arch trellis of FIG. 1 shown in a seventh environment of use.

(Continued)

FIG. 18 is an enlarged view of detail 18 in FIG. 1; and, FIG. 19 is an enlarged view of detail 19 in FIG. 1. The dashed broken lines depict portions of the garden arch trellis that form no part of the claimed design. The dot-dash broken lines in FIGS. 1, 18, and 19 depict the boundaries of the enlarged views and form no part of the claimed design. The additional dashed broken lines in FIGS. 11-17 depict environmental structures that form no part of the claimed design.

1 Claim, 19 Drawing Sheets
